ELECTRIC CUT-OUT

Edmund O. Schweitzer, Chicago, Ill.

Application June 12, 1930. Serial No. 460,582

19 Claims. (Cl. 200—120)

This invention relates in general to circuit interrupters known as "fused cut-outs" wherein a fuse is mounted in a chamber containing oil or other insulating liquid, although the invention is not limited to such an arrangement. A cut-out of this type is shown in the Patent No. 1,479,588 of January 1, 1924, granted to myself and Alfred Herz.

Briefly, this cut-out comprises a fuse link which is mounted between two compression blocks of wood or other suitable insulating material and the whole submerged in a bath of oil or other suitable insulating liquid. When the current flowing through the fuse becomes excessive the fuse blows to interrupt the circuit, the oil being relied upon to quickly quench the arc that may be formed upon the blowing of the fuse.

When a fuse blows in oil it not only spoils the oil but it also coats the inside of the cut-out and everything therein with a layer of carbon which is highly objectionable in that it constantly breeds trouble. It is an object of the present invention to provide a cut-out which overcomes this difficulty. There are two types of overload for which the cut-out renders protection. One of these types is an overload of the kind which is slightly above the capacity for which the circuit is designed and which is injurious only if it lasts for prolonged periods of time, and the other is the very heavy overload of high destructive possibilities and which must be guarded against instantly. The former type of overload is far more frequent than the latter and it is one of the objects of the present invention to provide a cut-out which will avoid the contamination of the oil or other insulating liquid when the same interrupts a circuit upon a light overload while, at the same time, affording protection against heavy overloads. Upon the occurrence of a large overload the fuse blows to interrupt the circuit in the usual manner. In order to protect the circuit against small but continuing overloads I provide a bellows or other thermo expansive member which is adapted to be expanded by the heat generated due to the current flow through the circuit. When the load carried by the fuse is excessive the heat of the fuse will expand the expansive member to trip a catch holding a small quick acting switch blade that is connected in series with the fuse. Should the load reach a certain predetermined value which is very much in excess of the maximum instantaneous load to be carried by the circuit the fuse will blow to immediately interrupt the circuit with-

out delaying until the expandable member is heated sufficiently to bring about the tripping of the switch. The fuse may be mounted adjacent the bellows on the outside thereof and suitable heat conducting means may be provided to conduct the heat of the fuse to the bellows. On the other hand, the fuse may be mounted within the bellows itself, the bellows being filled with oil, or other insulating liquid, or it may be mounted in a small receptacle which communicates with the liquid within the bellows. The bellows is substantially filled with insulating liquid, but the liquid content thereof should be a small percentage of the total oil in the tank. The bellows may be filled with oil, carbon tetra-chloride, ether, or the like.

Most of the oil cut-outs are employed in the protection of transformers to promptly disconnect a defective transformer so that it may not interfere with the service of the remaining apparatus on the same circuit. Certain apparatus which may be connected to the transformer, such as motors or the like, may take a starting current of from two to five times the continuous current carrying capacity of the transformer. In order to prevent interruption of the transformer circuits when a motor drawing such heavy current is being started it is necessary to employ fuses whose continuous capacity is from two to five times the capacity of the transformer. Transformers are, naturally, not designed to stand even as much as a 50% overload for two or three hours, hence when an overload of 100% is connected to a transformer for any appreciable period of time the transformer burns up since the fuse affords no protection.

To avoid the destruction of a transformer upon the occurrence of such an overload, on the theory that such overloads are unavoidable, thermometers, semaphored thermal indicators, or other indicating devices have been installed in each transformer and an inspector travels the line to see which transformers are running too hot. It is obvious that the inspector cannot be at each transformer when an unexpected load is thrown on due to some customer failing to notify the company of his new load. Therefore, thermal indicators cannot be relied upon to produce the desired results. In addition thermal indicators are of themselves a source of trouble.

In my improved cut-out the switch used is held in its closed position by a toggle which is arranged to be tripped by the expansion of the thermo expansive member. A tripping rod ex-

tends from the toggle mechanism to within a short distance of the thermo expansive member, this short distance determining the extent of permissible expansion of the member without 5 producing a tripping of the switch. This same rod extends upward of the switch above the oil level and constitutes a means for reclosing the switch. The rod may be adjusted towards and away from the expansible member in order to 10 vary the extent of permissible expansion without producing an operation of the switch. A calibrated scale is provided, preferably on top of but within the oil casing, for indicating the extent of permissible expansion of the thermal 15 element.

It is a further object of the present invention to provide an improved bushing structure for extending a conductor into a casing of the class described. The contacts for the switch mechanism are directly supported by the bushing structure and serve also to prevent the withdrawing of the circuit conductor that extends through the bushing.

In order to acquaint those skilled in the art 25 with the manner of constructing and operating a device of my invention, I shall describe in connection with the accompanying drawings a specific embodiment thereof, from which the attainment of the above and other objects of the 30 present invention will be apparent.

In the drawings:

Figure 1 is a plan view of my improved cut-out, the cover being removed;

Figure 2 is a view in partial section taken 35 along the line 2-2 of Figure 1, certain of the parts being shown in section and others being shown in elevation;

Figure 3 is a sectional view taken along the line 3-3 of Figure 2 and looking in the direction 40 of the arrows;

Figure 4 is a bottom view of the fuse mechanism with the bottom fuse cover removed;

Figure 5 is a fragmentary sectional view of 45 the toggle link adjusting means, said view being taken along the line 5-5 of Figure 2 and looking in the direction of the arrows;

Figure 5a is a view similar to Figure 5 and showing an alternate form of construction;

Figure 6 is a fragmentary sectional view of 50 a modified form of thermal connection between the fuse and the bellows;

Figure 7 is a fragmentary sectional view corresponding to Figure 1 and showing a modified 55 form of my invention;

Figure 8 is a sectional view taken along the line 8-8 of Figure 7 and looking in the direction of the arrows; and

Figure 9 is a fragmentary end view of the operating mechanism.

Referring now more particularly to the drawings, the cut-out comprises an open top casing 1 which is adapted to receive the various operating parts and which is filled with insulating oil or other insulating liquid to a level as indicated by the line 2. The casing is provided with a novel bushing structure for leading the line conductors into the casing. The bushing includes a bushing shield comprising a pair of nipples 3-4, and insulating sleeves 5 through 65 which the conductors 6 extend. The nipples are forced through suitable openings in the casing 1, said nipples making a press fit within the openings. The insulating sleeve 5 having the conductor 6 fitting tightly therein is itself pressed 70 into the nipple 4, said sleeve being pressed up-

ward into the casing from the bottom side of the nipple. The insulator 5 is provided with a flange 6' having an upper tapered surface 7 that seats against a corresponding tapered surface at the inner bottom side of the nipple and limits the extent of inward movement of the insulating sleeve 5 within the casing 1. Since the various parts are press fitted within one another leakage of insulating liquid from within the casing 1 is prevented. The conductor 6 has a portion 8 extending beyond the insulating sleeve 5, constituting means for establishing a connection with a suitable conductor for extending a circuit through the cut-out. Prior to the making of the connection with the incoming line conductor, a guarding sleeve 10 and a clamping nut 11 are slipped over the end of the conductor and, upon the completion of the electrical connections with portion 8 of the conductor 6 the guarding sleeve is brought up to bear against the flange 6' of the insulator 5, said sleeve and said flange being both provided with co-operating tapered portions forming a conical seat 12. The clamping nut 11 is then threaded to the bottom of the nipple 4 and, at the shoulder 13, it clamps the guarding sleeve 10 and the insulator 5 against the nipple 4 thus effectively securing both of those members against outward withdrawal. A contact terminal 15 having a pair of projecting ears 16 is clamped to the end of the conductor 6 within the casing 1 by means of a suitable screw or bolt 17. The contact 15 is tightly clamped around the conductor 6 and it rests against the insulating sleeve 5 thereby preventing the withdrawal of the conductor 6 through the sleeve and out of the casing.

The top of the casing 1 is provided with an inturned circular rim or flange 18 upon which is adapted to be seated a circular disc 19 from which is suspended the various operating parts, 115 and a cover 20. A pad 21, of felt or the like, is interposed between the cover 20 and the flange 18 in order to provide an effective seal to prevent the entrance of moisture or other foreign material into the casing. The cover 20 is bolted 120 to the flange 18 by means of six bolts indicated at 22.

A block 25 of suitable insulating material is suspended from the top disc 19 by means of four studs 26 which may be locked in place by 125 means of nuts 27. The studs 26 are threaded into corresponding holes in the block of insulation 25 and are locked against turning, by nuts 29. Two threaded studs 40 extend through openings in the block 25 on opposite sides of the center thereof and are locked thereto by lower nuts 41 and an upper washer 42 and an upper nut 43. The studs 40 are made of copper or other metal of high electric conductivity. Laminated spring contacts 45 are mounted between the lock nut 43 and the washer 42 and are held in firm electrical contact with the stud 40 by means of the nut 43. A pivot member 48 is welded or otherwise secured to the left hand contact spring 45 and a similar member 49 is similarly secured to the right hand contact spring 45. The member 48 is pivoted between two arms of a link 51 by means of a pin 52 which extends through a circular hole in the arms of the member 51 and through a similar hole in the member 48, said member 48 being rotatable with respect to the arms of the link 51. The member 49 is similarly pivoted between the two arms of a link 55 similar in construction to the link 51. The two links 51 and 55

are pivotally connected together by means of two pins 56 and 57 located at the opposite sides of the sets of links, said pins extending through holes in the adjacent ends of the links and screwing into a nut 58 that lies between the two arms of the link 51. The nut 58 comprises merely a square block which fits between the two arms of the link 51 and which is provided with a central opening for receiving an operating shaft in a manner to be more fully set forth as the description proceeds. The links 51 and 55 are made of suitable electrical insulating material so as not to constitute a short circuit between the contact springs 45 and they 15 constitute a toggle for forcing the contacting ends of the springs 45 into engagement with the contacts 15 mounted within the casing 1 as previously described. The links 51 and 55 constitute a toggle which is on dead center when the switch is in its closed position, as illustrated, and which is forced to the open position by the action of the spring pressure of the contacts 45 when the toggle is knuckled slightly upward.

20 25 An actuating or tripping rod 59 is screw threaded through an internally threaded opening in the member 58, being locked in place by means of a lock nut 60. The lock 60 may be omitted if desired. It is to be noted that the block 58 is pivoted between the links so that it may remain horizontal when the toggle breaks. A block 65 of insulating material is suspended from the studs 40, and a fuse link 66 is removably mounted on the bottom side of the block 35 40 45 50 55 60 65 70 75 80 85 90 95 100 105 110 115 120 125 130 135 140 145 150 65 70 75 80 85 90 95 100 105 110 115 120 125 130 135 140 145 150

The block 65 has a cylindrical bore 75 formed therein at its center and extending upwardly from the bottom for a distance approximately half way through the block. Six small holes indicated in general at 76 are drilled through the remaining portion of the block 65 above the end of the bore 75. An expansible member or chamber 78 which may be of any suitable construction and which in the modification herein shown comprises an expansible bellows, is mounted upon the block 65 and is provided with a projecting stud 80 which projects through a central opening in the block 65 and extends downwardly into physical contact with the fuse 66. The projecting stud 80 is made of suitable heat conducting material so as to conduct heat from the fuse to the material within the bellows 78.

65 70 75 80 85 90 95 100 105 110 115 120 125 130 135 140 145 150

A second compression block 86 of suitable insulating material is bolted or otherwise suitably secured to the bottom of the block 65 and constitutes a cover for the fuse. The block 86 is provided with depressions into which the screws 67 seat and is secured to the block 65 by means of two screws 87 (Figure 4) that pass into tapped holes in the block 65. The compression block 86 is provided with a rectangular slot 88 for permitting the oil or other insulating liquid within the casing 1 to circulate around the fuse. A cylindrical sleeve 89 of suitable heat insulating and electrical insulating material extends

between the blocks 25 and 65 and surrounds the bellows, being spaced therefrom. The purpose of this sleeve is to limit the extent of circulation of the liquid within the casing 1 around the bellows. Thus the oil that is heated by the fuse rises into the space between the bellows and the sleeve and serves to effectively heat the bellows. In addition the sleeve prevents the accidental contact between the bellows and the studs 40-40. It is within the purview of the present invention to omit the sleeve if desired.

The bottom of the actuating or tripping rod 59 extends into a short cylindrical bore in a fitting 90 on the top of the bellows 78. The bottom of the rod 59 terminates a short distance from the end of the bore in the fitting 90 whereby a limited amount of expansion of the bellows is permitted without producing any effect upon the rod 59. Upon further expansion of the bellows the rod 59 is moved upwardly, moving the knuckle of the toggle links 51-55 upwardly to break the toggle and permit the spring contacts 45 to force the switch to snap open.

An explanation will now be given of the manner of operation of my improved circuit interrupter. When the switch is in the closed position a circuit extends from the conductor 6, through the terminal contact 15, through the end 91 of the right hand spring contact 45, the right hand stud 40, the fuse 66 and the left hand stud 40, thence by way of the left hand spring contact 45 and the left hand terminal contact 15 through the conductor within the left hand bushing. The fuse 66 is purposely made of a capacity greatly in excess of the continuous current capacity of the circuit in which it is connected, this being provided for the purpose of permitting the starting of motors or like apparatus which take a starting current greatly in excess of the normal running current. This may exceed three times the normal running current. It is apparent that a fuse of a capacity of two and one-half times the rated capacity of the apparatus to which it is connected will not, of itself, afford any protection against continuous overloads of say a magnitude of 50%. If a smaller fuse were used then it would promptly blow upon the occurrence of a momentary overload such as would occur upon the starting of a large motor or the like. The present apparatus overcomes these difficulties. Should the load current exceed the rated amount for which the fuse is designed, the fuse will commence to overheat and should the overload continue for an extended period of time the liquid adjacent the fuse will be appreciably heated. The bulk of the heated liquid will rise and will act to heat the liquid within the bellows 78. In addition, the stud 80 which is in close proximity to the fuse link and therefore in the region of the hottest liquid, will conduct heat to the liquid within the bellows. The bellows may be filled with oil of the same kind as is contained within the casing 1, or it may be filled with any other liquid having an appreciable coefficient of expansion at the temperatures used. Carbon tetra-chloride, ether, or the like may be used. Upon being heated, the liquid within the bellows will expand thereby expanding the bellows. It is to be understood that the liquid within the entire casing 1 will also be heated but due to the construction of the cut-out, as shown, the temperature gradient will be such that the liquid in the region of the bellows will be heated sooner and to a higher tem-

perature than will be the rest of the body of liquid in the casing 1. Upon the expansion of the liquid within the bellows the top of the bellows comes into engagement with the bottom 5 of the actuating or tripping rod 59. Upon further expansion of the bellows the rod 59 is moved upwardly thereby moving the knuckle of the toggle 51-55 upwardly and out of dead center. The spring contact members 45 being 10 under stress now act through the members 48 and 49 to force the knuckle of the toggle upwards, the members 48 and 49 pivoting about the respective links 51 and 55 at the pins 52. The ends 91 of the contact brushes 45 thereby move 15 out of engagement with the terminals 15, thus breaking the circuit between the conductor 6 and the corresponding conductor in the left-hand terminal bushing. It is to be noted that the tripping of the switch is dependent upon the 20 expansion of the liquid within the bellows 78, which expansion is not dependent upon the existence of a temperature difference between the liquid within the bellows and that outside of the bellows. Thus, even if there should be a circulation 25 of the liquid outside of the bellows, that is the liquid within the casing 1, the switch would nevertheless be tripped upon the occurrence of a continuing overload. When the switch trips, the plunger 59 is moved upwardly, 30 said plunger extending through an opening in the top 20 of casing and into a sleeve 92 which is closed at its outermost end is threaded into the cover member 20.

To reset the switch, the cap portion 92 is 35 screwed and the operating rod or plunger 59 is pushed downwardly. This forces the contact springs 45 back into engagement with the contact 15 thereby assuming the position shown in full lines in Figure 1. In order to limit the extent of downward motion of the knuckle of the toggle comprising the links 51-55, one of the links 55 is extended beyond the knuckle as indicated at 55' and is provided with an extended portion 55a which engages the pin 52 when the 40 links 55 and 51 reach a position of alignment. For this purpose the pin 52 is extended beyond the link 51 at one end thereof. It is thus merely necessary to depress the operating rod 59 45 downwardly as far as it will go in order to bring the switch into its full closed position.

From the description thus far given it is apparent that the distance between the bottom of the tripping rod 59 and the bellows 78 when the switch is closed will determine the extent of 55 permissible expansion of the bellows without operating the switch. In order to vary the extent of permissible operation of the bellows the rod 59 may be adjusted lengthwise of the member 58 to bring the bottom of the rod closer to 60 or further away from the bellows. This may be accomplished by loosening the lock nut 60 (Figure 5), if such a nut is provided, and then rotating the rod 59 to lower it. The disc 19 is 65 calibrated as indicated at 95 and a pointer 96 is mounted upon the operating rod 59 so that upon turning of the operating rod to advance the rod towards or away from the bellows the pointer 96 moves across the calibrated scale 95 to indicate the extent of permissible operation of the 70 bellows. The pointer 96 is preferably mounted upon the rod 59 so as to be freely slideable with respect thereto to a limited extent but it is non-rotatable with respect to the rod 59. This may be accomplished by making the rod 59 square 75 at its end. This will permit the free rising of

the operating rod 59 when the switch is tripped. When the operating rod rises due to the tripping of the switch the pointer 96 may be held against rising by engagement thereof with the cover 20. It is, of course, to be understood that any other desirable arrangement may be provided for indicating the extent of turning of the rod 59 and thereby indicating the extent to which the rod has been advanced towards or withdrawn from the bellows. As an alternative arrangement the central opening in the block member 58 need not be internally threaded. The rod 59 extends freely through the opening and is held in place by means of a pair of lock nuts 60-60 as shown in Figure 5a. In such an arrangement it is necessary to withdraw the operating mechanism from within the casing 1 in order to adjust the rod 59 to vary the extent of permissible operation of the bellows 78.

Should an exceedingly heavy overload such as a short circuit or the like occur upon a line which is being protected by my improved cut-out then the circuit will be interrupted instantly by the blowing of the fuse. This is necessary because under such circumstances it would be 100 poor practice to permit the short circuit to continue until the liquid within the bellows 78 has heated sufficiently to cause the tripping of the switch. To replace the fuse the entire mechanism must be removed from the casing 1. This 105 may be accomplished by first removing the cover 20 and then lifting the disc 19 outwardly. Upon the removal of the disc 19 the studs 26 are likewise removed since the studs rest within the disc and removal of one brings about the removal of 110 the other. The entire mechanism is thus lifted out of the casing by the lifting therefrom of the disc 19. It is to be noted that the diameter of the block 25 and the diameter of the block 65 is such as to permit their withdrawal past the 115 contacts 15-15 and through the opening in the flange 18 of the casing. The casing is provided with a drain plug 94 permitting draining of the oil or other insulating liquid within the casing thereby permitting the cleaning of the casing 120 and the replacement of the oil therein by fresh oil whenever necessary.

As a modification of the above described structure I propose to mount the fuse 66 within a casing 101, of glass or the like, and connected in 125 circuit in the same manner as is the fuse shown in Figure 2. The modification is shown in Figure 6. In this form of my invention the stud 80' is made in the form of a tube or the like establishing communication between the inside 130 of the bellows 78 and the inside of the casing 101. In this arrangement the bellows and the casing 101 may be filled with oil, carbon tetrachloride, ether, or any other suitable insulating liquid which preferably has a high coefficient of 135 expansion. In this arrangement, upon the occurrence of a slight but continuing overload, the heat generated by the fuse heats the liquid within the casing 101 and within the bellows 78, since the two are in communication, thus expanding the bellows to bring about the operation of the switch. Upon the occurrence of a greater overload the fuse will blow, but if the overload is not too severe the glass 101 will not be shattered hence the arc of the fuse will be quenched 140 by the liquid in the tube 101 which is of greater insulating quality than the oil. If the arc is not quickly quenched, the gases generated by the arc may cause an expansion of the bellows to trip the switch, thus insuring the interruption 145 150

of the circuit without the contaminating of the oil in the casing 1. Upon the occurrence of a very severe overload the glass 101 will be shattered thus rendering the oil or other insulating

- 5 liquid within the casing 1 available for quenching the arc produced by the blowing of the fuse. In addition, it is to be noted that the liquid within the bellows is under a certain amount of pressure due to the elasticity of the bellows itself, hence
10 when the fuse blows the bellows will tend to collapse and force the carbon tetra-chloride directly into the region of the arc with a certain amount of force thereby tending to quickly quench the arc. This is advantageous for two
15 reasons. First, due to the velocity of the liquid issuing from the member 80' there will constantly be fresh cooling liquid within the region of the arc tending to quickly cool the same. Secondly, the carbon tetra-chloride or the ether
20 has higher insulating properties than the surrounding oil. The addition, due to their low boiling point, they will quickly vaporize and, by extracting the heat necessary to vaporize them, namely the heat of vaporization, they will additionally cool the region of the arc and thus tend to quicker extinguish the same. The member 80' has the effect of a nozzle which is directed into the region of the arc to quench the arc by a blowout and a cooling action. The bellows
25 30 with the insulating liquid therein is thus of use in the case of a slight but continuing short circuit in that the expansion thereof causes a tripping of the toggle switch, and it is of use during a very severe short circuit in that it tends to project the liquid from the bellows into the region of the arc to quickly and effectively quench the arc.

It is well known that hot insulating liquid has lower arc quenching properties than the same liquid has when cold. Now, when a severe overload is preceded by a slight overload of an extended duration the liquid ejected through the tube 80' is quite hot due to the previous heating of the same. To make up for the decrease in the arc quenching ability of the liquid, the liquid is ejected through the region of the arc at a greater velocity due to the fact that the hot liquid has expanded the bellows which now exerts a greater pressure upon the liquid.

50 Reference may now be had more particularly to Figures 7, 8 and 9 wherein I show a modified form of my improved circuit interrupter. In this form of interrupter the block 65 is mechanically supported from the block 25 by means of two studs 40 and 40'. The stud 40 is made of copper or other suitable conducting material and is electrically and mechanically connected in the same manner as is the stud 40 at the right hand side of Figure 2. The stud 40', on the other hand, is made of insulating material and is mechanically mounted in substantially the same manner as is the stud 40. A washer 42 of copper or other suitable conducting material is interposed between the block 25 and the nut 43 that clamps the springs 45 in place. This washer extends the electric circuit from the left hand spring 45 to a stud 125 of copper or the like that extends through the block 25 and is threaded into a block 126 which is mounted upon the compression block 65 on the upper side thereof. The end 127 of a coiled thermo expansion spring 128a rests upon the copper block 126 and is provided with a perforation through which the stud 125 extends, said stud being locked to the block 126 and to the end 127 of the thermal element

128a by means of a lock nut 129. The inner coiled end of the thermal spring is electrically and mechanically connected to a shaft 130 which is made of copper or other suitable metal of high electrical conductivity and which is supported in two bearings 131 and 132 so as to be freely rotatable. A coiled thermal spring member 128b which is of a construction substantially identical to the spring 128a is secured to the opposite end of the shaft 130. The outer end 127 of this last mentioned thermal spring rests upon a copper block 135 which is secured to the upper side of the compression block 65. A bolt 136, of copper or the like, extends through a perforated opening in the end of the thermal spring 128b, said bolt extending through the block 135 and through the compression block 65 and being threaded into a block 69' of copper that is secured to the lower side of the compression block 65. This copper block 69' corresponds in function to the block 69 shown in Figures 2 and 4. The insulating stud 40' extends through the compression block 65 and is threaded into a suitable threaded opening in the copper block 69' thus supporting the block 69' and the compression block 65 which rests thereon. A fuse 66 is mounted on the bottom side of the compression block 65 in the same manner as is mounted the fuse 66 of Figure 2, previously described.

100 A compression block 86 similar to the corresponding block in the cut-out previously described is mounted upon the lower side of the compression block 65, said former block being provided with a rectangular opening 88 therein for permitting oil or other insulating liquid within the casing 1 to circulate around the fuse link. The block 65 is provided with a central hole 140 and a plurality of spaced holes 141 extending therethrough immediately above the fuse link. Oil that is heated by the fuse link may rise through these openings into the space between the blocks 25 and 65 and act to heat the thermal expansion springs 128a and 128b. This is in addition to the heating effect upon these springs of the current flowing through them. If desired a shield member corresponding to the member 89 in the cut-out previously described may be here provided for confining the heated oil within the region of the thermal expansion members 128a and 128b, although this is not indispensable.

110 The shaft 59 for tripping the toggle switch extends to within a short distance of the rotatable member 130 and this last mentioned member is provided with a cam 145 which is keyed thereto immediately below the bottom of the shaft 59. This cam member may take the form of a rectangular block or the like. Upon rotation of the shaft member 130 the cam 145 forces the operating rod 59 upwardly to break the toggle switch thereby permitting the spring contact 45 to trip.

120 The circuit for the cut-out extends from the right hand contact 15, through the right hand spring contact 45 and the stud 40 to the block 68, thence by way of the fuse 66 and the block 69' to the stud 136 and the thermal spring 128b. Thence the circuit extends by way of the shaft 130 to the thermal spring 128a and the block 126. From the block 126 the circuit extends through the copper stud 125 to the washer 42 and thence to the left hand contact spring 45 and the left hand contact 15. Should an excessive current flow through the cut-out for 130 135 prolonged periods of time the thermal expansion

sion springs 128a and 128b will be heated by the excessive current flowing therethrough. In addition the oil or other insulating liquid surrounding these springs will be heated by the excessive current flowing through the fuse 66 since the heated oil in contact with the fuse rises through the central opening 140 and the spaced openings 141. The thermal expansion springs upon being heated tend to uncoil and thereby rotate the shaft 130 through a limited angle. This produces a rotation of the cam 145 bringing this cam into engagement with the operating rod 59. Upon further rotation of the shaft 130 the cam forces the operating rod 59 upwardly to trip the switch in the manner previously set forth. Upon the occurrence of a very large overload the fuse 66 will blow instantly to immediately interrupt the circuit without waiting for the heating of the thermal expansion members.

In compliance with the requirements of the patent statutes I have herein shown and described a few preferred embodiments of my invention. It is, however, to be understood that the invention is not limited to the precise construction of the embodiments herein shown but is capable of modification, the embodiments herein shown being merely illustrative of the principles of my invention. What I consider new and desire to secure by Letters Patent is:

1. A switch comprising a pair of stationary contacts, a pair of spring contacts adapted to engage the stationary contacts, a toggle for maintaining the contacts in engagement, said toggle being substantially on dead center and maintaining the spring contacts under stress when the switch is closed, means for breaking the toggle, whereby the stress on the spring contacts is released and the contacts snap away from the stationary contacts to open the circuit, and thermal means for actuating said last named means, said first means including means for varying the distance to the thermal means for varying the point of operation of the switch.

2. A switch comprising a pair of stationary contacts, a pair of spring contacts adapted to engage the stationary contacts, a toggle for maintaining the contacts in engagement, said toggle being substantially on dead center and maintaining the spring contacts under stress when the switch is closed, means comprising a member extending through the toggle for breaking the toggle, whereby the stress on the spring contacts is released and the contacts snap away from the stationary contacts to open the circuit, and thermal expansion means including an electric fuse for actuating said last named means, said first named means being adjustable towards and away from the thermal means whereby the point of operation of the toggle is altered.

3. An electric switch including a casing, a switch closing and opening rod extending from the casing to the outside thereof, and movable means spaced from the end of the rod within the casing and movable into engagement therewith for tripping the switch, said rod being adjustable towards and away from the movable means for altering the extent of permissible movement of the movable means before the same actuates the tripping rod.

4. An electric switch including a casing, a switch closing and opening rod extending from the casing to the outside thereof, a removable cap member secured to the casing and enclosing the end of the rod, and movable means spaced

from the end of the rod within the casing and movable into engagement therewith for tripping the switch, said rod being adjustable towards and away from the movable means for altering the extent of permissible movement of the movable means before the same actuates the tripping rod.

5. A switch including an open top casing, contacts mounted therein, a switching mechanism suspended within the casing and including movable contact making members adapted to engage the contacts, and means for tripping the contact making members out of engagement with the contacts, and a removable cover independent of the switching mechanism for covering the casing and preventing removal of the switching mechanism from the casing.

6. An electric switch including a casing, a bushing extending an incoming conductor into the casing, a switch contact mounted on and supported by the bushing structure, and a removable switching mechanism inserted into the casing and including a contact making member adapted to engage the contact, said mechanism including means operable while the mechanism is within the casing for snapping the contact making member out of engagement with the contact to interrupt the circuit.

7. An electric switch including a casing, a bushing extending an incoming conductor into the casing, a switch contact mounted on and supported by the bushing structure, and a removable switching mechanism inserted into the casing and including a contact making member adapted to engage the contact, said contact making member being held in engagement with the contact against spring tension urging it away from the contact, said mechanism including means for holding the contact making member in engagement with the contact and means for releasing the same.

8. A cut-out mechanism comprising a mounting ring member, a pair of blocks suspended from the mounting ring member, a switch mechanism mounted on one of the blocks, a thermal element mounted on the other block, switch tripping means extending into the region of the thermal means and spaced therefrom so that upon a predetermined expansion of the thermal means the switching means is tripped open, and means extending through the ring member for varying the spacing between the tripping means and the thermal means.

9. A switch including a toggle mechanism, spring means for urging the toggle to the open position, a shaft extending through the knuckle of the toggle for actuating the same to the closed position against the action of the spring and for initiating the switch opening movement of the toggle, an expansible element spaced from one end of the shaft and expansible into engagement therewith for moving the same to trip the toggle, the position of said shaft in the toggle being adjustable for adjusting the distance between the end of the shaft and the expansible element thereby adjusting the point of operation of the toggle, and calibrated means adjacent the opposite end of the shaft for indicating the point of operation of the toggle.

10. A circuit interrupter comprising a relatively small fluid containing means within a relatively large casing, circuit interrupting means within the fluid containing means, arc extinguishing fluid within the containing means and within the casing, and means including a dis-

charge passageway for ejecting fluid from the first mentioned means into the large casing through the region of the arc upon the interruption of the circuit.

5 11. A circuit interrupter comprising two chambers containing arc quenching liquid and communicating with one another through a restricted opening, means in one of the chambers for interrupting a circuit and drawing an arc adjacent

10 the opening, the liquid in the other chamber being ejected through the opening into the region of the arc upon the opening of the circuit at the circuit interrupting means.

12. In combination, a fragile casing, a fuse

15 therein adapted to break the casing upon blowing of the fuse, a second casing containing arc quenching liquid under pressure and communicating with the first mentioned casing at the point of arc formation by the fuse, whereby the liquid from the second casing flows through the region of the arc upon breaking of the fragile casing thereby serving to quench the arc.

13. In combination, circuit interrupting means and a bellows containing arc quenching liquid

25 and having an opening directed into the region of the arc formed by the circuit interrupting means.

14. In combination, a casing, circuit interrupting means therein, a contractible member

30 within the casing, said member containing arc quenching liquid and having an opening directed into the region of the arc formed by the

circuit interrupting means, and a bath of insulating liquid submerging the contractible member and the circuit interrupting means.

15. A circuit interrupter comprising a switch, a thermal element and a fuse in series, said fuse being adapted to heat the thermal element, and means actuated by the thermal element for opening the switch.

16. Circuit interrupting means including an electrothermal element and a fuse connected in series and immersed in a bath of insulating liquid.

17. Circuit interrupting means including an electrothermal element and a fuse connected in series and mounted to facilitate a heat exchange between them, said fuse and thermal element being immersed in a bath of insulating liquid.

18. In combination, a toggle switch, a fuse, and a thermal expansion element connected in series, said fuse and said thermal element being in heat exchange relation, and means controlled by the thermal element for tripping the toggle of the switch, said thermal expansion element and said toggle switch being immersed in a bath of insulating liquid.

19. A block of insulation having a fuse mounted on one side thereof, and a thermal element mounted on the other side thereof and electrically connected in series with the fuse, said block being arranged to facilitate a heat transfer from the fuse to the thermal element.

EDMUND O. SCHWEITZER.
